UNITED STATES PATENT OFFICE.

LOUIS M. FRANK, OF PHILADELPHIA, PENNSYLVANIA.

DESIGN FOR A HOOD.

SPECIFICATION forming part of Design No. 17,728, dated September 20, 1887.

Application filed March 25, 1887. Serial No. 232,452. Term of patent 3½ years.

To all whom it may concern:

Be it known that I, LOUIS M. FRANK, a citizen of the United States, residing in the city and county of Philadelphia, State of Pennsylvania, have invented and produced a new and original Design for a Hood, of which the following is a specification, reference being had to the accompanying photograph, forming a part thereof.

10. The leading feature of my design for a hood is the crossed front of the same.

A represents the body of the hood, which is somewhat of conical form and turned down at top, as at a. The front of the hood is

crossed, as at b. At the top are pompons or 15 ornaments c.

I claim—

A design for a hood herein shown and described, the same consisting of a conical body, the top portion of which is turned down on 20 the body, and the lower portion having a crossed front, and having pompons at or near the said turned-down top and on the body.

LOUIS M. FRANK.
